CLAIM

The ornamental design for a print wheel cartridge or the like, substantially as shown and described.

DESCRIPTION

FIG. 1 is a front perspective view of a printer wheel cartridge, or the like, showing our new design;
FIG. 2 is a front elevational view thereof;
FIG. 3 is a rear elevational view thereof;
FIG. 4 is a right side elevational view thereof, the left side being a mirror image;
FIG. 5 is a top plan view thereof; and
FIG. 6 is a bottom plan view thereof.
